UNITED STATES PATENT OFFICE.

OLOF OHLSSON, OF SÖDERTELJE, SWEDEN.

CONSTANT-PRESSURE INTERNAL-COMBUSTION ENGINE.

1,324,406.

Specification of Letters Patent.

Patented Dec. 9, 1919.

Application filed April 27, 1915. Serial No. 24,192.

To all whom it may concern:

- Be it known that I, OLOF OHLSSON, a subject of the King of Sweden, and resident of Skogsgatan 3, Södertelje, in the Kingdom of Sweden, have invented certain new and useful Improvements in Constant-Pressure Internal-Combustion Engines, of which the following is a specification, reference being had therein to the accompanying drawings.
- 10 In constant-pressure engines hitherto known the fuel must be fed into the same by means of compressed air, which evidently renders the engine so expensive and complicated that the said feeding means cannot be used in engines of the small types.
- 15 This invention relates to a constant-pressure engine in which the fuel is fed in without air at a constant position of the crank, i. e. when the piston passes the position at 20 the outer dead center and the compression is the greatest one, and at the same time there is no fuel in the cylinder during the compression stroke. Owing to the said fact the engine can operate with the necessary 25 high pressure during the compression stroke or with the necessary high temperature, thus with a considerable excess of pressure and temperature necessary for the ignition and the combustion, the ignition being thereby 30 constant at all working conditions, no regulation being thus necessary. Consequently, the object aimed at consists in the engine being quite free from gas mixture or fuel during the compression stroke. For the 35 gaining of the said object three main factors are necessary, viz. a very rapid gasification of all fuel fed in, and a complete combustion of the said fuel during the working stroke for which it is intended, further 40 the gas must be blown out in a more effective manner than what is generally the case in engines.

In the accompanying drawings

- 45 Figure 1 is a longitudinal section, partly a side elevation, of what is necessary for the description of this invention.

50 Figs. 2 and 3 are sections on the line A to B of Fig. 1 and show the working piston in different positions.

55 Fig. 4 shows the working piston viewed toward the inner end of same.

Fig. 5 shows a modified form of the invention.

For gasifying the fuel a so called finely 55 dividing valve 1 before known and spring-loaded, if wanted, is preferably used, the

end of same being located, according to this invention, within an ignition device, carburetor or preliminary combustion chamber 2 which is provided in the working chamber 60 of the cylinder and in which a high temperature is prevailing. In the drawings the said ignition device consists of a cylindrical body, which is open at the end facing the valve 1 and provided at its other closed end 65 with a plurality of openings 3. Thus, the ignition body communicates with the working chamber of the cylinder at its open end and through the openings 3. Owing to the said arrangement of the ignition device the 70 valve end is put in contact with the most effective combustion flame escaping from the rear large outlet opening of the ignition body, so that the valve is heated to the degree necessary for gasifying the fuel in 75 the moment when the same is forced through the hot valve at a high pressure. Owing to the said arrangement the whole amount or approximately the whole amount of fuel is 80 gasified instantaneously.

85 The fuel may not be thrown from the valve 1 directly into the working chamber of the cylinder, as it is quite impossible to maintain the walls of the entire working chamber at the necessary high temperature, and besides the gas is so diluted at a small load that the combustion cannot be finished while the necessary high pressure is still prevailing in the cylinder. For this reason 90 the fuel (being in a substantially gasified condition) is fed in in a tubular shape and in a thin layer along the inner walls of the strongly heated ignition body holding only a certain portion of the compressed air volume. The air forming a core within 95 the ignition device or body thus heated will evidently have a much higher temperature than the air located outside the ignition body and surrounded by the outer walls of the working chamber. The proportion of 100 the air volume of the ignition body to the whole air volume must be adapted in such a manner that, at a relatively small load of the engine, the air volume of the ignition body is approximately proportional to the 105 quantity of fuel, so that the combustion (being limited in this case to the very ignition body) takes place in a rapid and complete manner, in consequence whereof the engine works economically even at a small load. 110 If, however, the engine works at a full load, the air volume of the ignition body is in-

sufficient for the combustion of the quantity of fuel fed into the same, but owing to the increased pressure of the gas contained in the body which results from the preliminary combustion taking place in the same the gas is thrown out into the air which surrounds the ignition body and to which the combustion is now transmitted. By the said arrangement the combustion period is considerably prolonged, and the initial pressure is considerably lower, but the pressure remains constant or approximately so during a certain part of the working stroke.

As already mentioned, the fuel is fed to the inner walls of the ignition body in a tubular shape, a core of air being left in the center of the said body. This is of the greatest importance, as the fuel in a very thin layer will thereby come into close contact with the whole inner surface of the heated ignition body, the fuel being forced in between the hot walls of the ignition body and the said core of air which has a higher temperature than the air surrounding the ignition body. In this manner it will be possible to complete very rapidly the gasification of that fuel which may perhaps pass the valve in a nongasified condition, and also to cause an effective ignition of the whole quantity of gas.

Fig. 5 shows a rotatable ignition body 2 which rotates at a high speed and feeds the fuel into the working chamber through apertures at different points of the ignition body. The fuel is thrown out at a high speed owing to the centrifugal force. Owing to the high rotary speed of the ignition body an efficacious circulation of air is effected in the direction of the arrows, so that the fuel or the flame is mixed thoroughly with the air and spread to the whole mass of air surrounding the ignition body. For the rotat-

ing of the ignition body a groove wheel 3 may be used, mounted on a trunnion 4 extending from the ignition body, as shown as an example in the drawings.

The circulation of air (whirl) occurring in the working chamber of common two stroke cycle engines and by which the blowing out of the said chamber is rendered very difficult is prevented according to this invention by a portion of the air current being led over a bridge 6 with a curved guiding surface and projecting upward from the piston to a comparatively high extent and extending from the inlet opening 7 to the outlet opening 8. By the said bridge the air current coming from the outlet side is prevented from running toward the inlet side and into the colder air current entering at the same. Consequently, the inlet side and the outlet side of the cylinder determined by the said bridge are uniform or approximately so.

Having now described my invention, what I claim as new and desire to secure by Letters Patent is:

In a constant-pressure internal combustion engine the combination of a rotatable ignition body located within the working chamber and communicating therewith and surrounded by the air at the compression stroke, means for rotating the ignition body, and means for feeding in the fuel, which means are so located with relation to the ignition body that the fuel is fed in along the heated inner sides of the ignition body, the fuel being divided, spread and mixed with the air owing to the rotation of the ignition body, substantially as described and shown in the accompanying drawings.

In witness whereof I have hereunto signed my name.

OLOF OHLSSON.
